UNITED STATES PATENT OFFICE.

PAUL SCHANDER, OF ELKINS PARK, PENNSYLVANIA, ASSIGNOR TO FLETCHER WORKS,
OF PHILADELPHIA, PENNSYLVANIA, A CORPORATION OF PENNSYLVANIA.

LAUNDRY RACK.

Application filed June 16, 1927. Serial No. 199,283.

My invention relates to new and useful improvements in laundry racks, and has for an object to provide a rack that will be efficient in service, cheap to construct, and simple to assemble.

As is well known to those skilled in the art, different forms of revolving racks are used in commercial laundries, so that the clothes may be placed in bags or nets and placed 10 on the racks, there generally being a small card with indicia thereon to designate the contents or ownership of the different bags or nets of clothes; these different cards being placed with the respective bags on certain 15 or respective hooks.

It is desirable to have the racks revolve so that time may be saved when placing the different bundles on the rack, as if the rack did not revolve, it would be necessary for the 20 operators to keep encircling these racks or supports.

The racks, as a rule, are rather large in circumference, often being six feet in diameter, and it is desirable, therefore, to have a 25 rack that may freely revolve and at the same time be strong enough to support the weight of the great number of bags that will be placed thereon.

One of the principal objects, therefore, 30 is to provide a relatively strong rack, which may be made up of a plurality of simple castings and a number of small bars together with one circular sheet of metal, all of the parts being relatively cheap to manufacture 35 and easily assembled by an ordinary mechanician.

With these and other objects in view, the invention consists in certain new and novel arrangements and combination of parts, as 40 will be hereinafter more fully described and pointed out in the claims.

Referring to the drawings,

Fig. 1 is a vertical sectional view;

Fig. 2 is a top plan of the rack;

45 Fig. 3 is a vertical sectional view showing a slight modification; and

Fig. 4 is a top plan view of the construction.

Referring now more in detail to the drawings, and to Figs. 1, 2 and 4 in particular, 50 there is shown a tripod formed of three separate legs 1, which may be castings or may be of pressed metal, and are bolted to a small casting 2 which forms a bearing or support for the metal shaft 3, which is supposed to tightly fit within this base 2.

About this central shaft are positioned two wheels 4 and 20, and it is the simple construction of these rack wheels that forms one of the principal parts of the present invention.

As heretofore mentioned, these rack wheels are relatively large, and it is desirable to have them as strong as possible, and at the same time as inexpensive as possible, to meet 65 with the ordinary business competition.

Referring now to Figs. 1 and 2, it will be seen that the rack wheel consists of a lower circular hub 5, which is preferably an iron or steel casting, while extending radially 70 therefrom are the integral lugs 6, which lugs also extend at an angle to the body of the hub. As may be seen in these Figures 1 and 2, they are upwardly inclined so that the brace bars or compression members 7 may be 75 riveted or bolted thereto. These hubs will be made up in large quantities, as there will be two of them for each complete rack.

This hub 5 has its counterpart or upper hub 8, but in this instance, the hub 8 is provided with radial lugs 9 extending at right angles to the body of the hub, so that spokes 10 may be bolted or riveted at their inner ends to the lugs 9, and extend in a horizontal plane.

85 The rack wheel 4 also consists of a rim formed of a circular band of steel 11 which is from 6 to 8 inches in height, and riveted about its inner periphery are the small castings 12, having a vertical portion 13, the right angular lug 14 and the tangential lower lug 15, the angle of this lug 15 corresponding to the angle of the lug 6 of the lower hub. After these castings 12 are riveted to the steel band, the brace rod 7 will be riveted or 90 bolted to the respective lugs 6 and 15 of the

hub 5 and castings 12. These brace rods form the compression members to rigidly support the rotatable wheel 4.

The spokes or tension members 10 are riveted at their inner end, as heretofore mentioned to the lugs 9 of the upper hub 8, while their outer ends are riveted to the lugs or flanges 14 of the castings 12, to thus complete the formation of the wheel proper.

10 Secured to the outer periphery of the band 11, which is actually the rim of the wheel, there is shown a plurality of hooks or arms 16 which may be bolted to the rim 11 or may be fitted with bayonet lugs to fit within bayonet slots (not shown) within the rim so that the hooks may be quickly removed if desired.

15 Above the lower wheel 4 on the shaft 3 is secured an adjustable collar 17 so that the second wheel 20 may be assembled like the previous wheel, and slipped over the shaft or central support 3, so that this wheel in turn may be revolved by the operator when hooking the different bags on the hooks.

20 A hub cap 18 may then be placed on the upper threaded portion of the shaft 3.

25 As far as the specification has proceeded, it will be seen that besides the central shaft and its legs, there are two wheels, each of which consists of simply a circular band, an upper and lower hub, a plurality of small castings, and the compression and tension members, all of which parts may be quickly bolted or riveted together to form a very strong wheel. At the same time, the wheel is strong enough to bear the weight of the many bags of clothes that will be supported on the different hooks.

30 Referring now to the slightly modified form as shown in Fig. 3, there is shown the same form of leg 25 secured to the casting 26, but this casting has a somewhat longer hollow hub 27 while secured to the lower flange 28 thereof may be bolted a small casting 29 in which there is fitted the thrust ball bearing 30, so that the supporting shaft 31 may rest therein and revolve freely within the hub 27 of the casting 26.

35 In the first form described, it will be remembered the shaft 3 is to be fixed, and the two wheels 4 and 20 were adapted to be rotated about the shaft. In the form now being described, the shaft 31 is to be rotatably mounted and the two rack wheels 32 and 33 are to be provided with set screws 34 so that the two wheels may be revolved in unison with the shaft 31, or if these set screws are loosened, either wheel is free to rotate thereon.

40 The wheels 32 and 33 with the exception of the set screws in the lower respective hubs are identical with the wheels 4 and 20 of the rack shown in Fig. 1.

45 The only major difference, therefore, is the construction of the housing at the bottom of the rack, so that the shaft 31 may be free to

rotate and thus permit the wheels to rotate in unison or the set screws may be loosened so that the wheels may be revolved independently of the central shaft.

50 From the foregoing it will be seen that I have designed a large rack capable of supporting the heavy load that will be placed upon it and at the same time, I have provided a rack wherein the assembly consists of simply riveting or bolting the tension and compression members to small castings that are in turn secured to a rim, and further providing an upper and lower hub with certain lugs thereon to which lugs are secured respectively the inner ends of the spokes or tension members, and the inner ends of the compression members.

55 I am aware that there are many different forms of wheels, but the present racks are exceedingly simple to assemble and necessitate but few parts to be bolted or riveted together by an ordinary mechanic.

60 Many slight changes might be made without in any way departing from the spirit and scope of the invention.

Having thus described my invention, what I claim as new and desire to secure by Letters Patent is:—

65 1. A laundry rack comprising a base, a central shaft rotatably mounted in the base, two wheel racks rotatably mounted on said shaft and means for locking each of them to said shaft, each of said wheel racks comprising a relatively wide flat metal rim, a plurality of castings secured to the inner periphery of the rim and said castings extending across the inner face of the rim and said castings provided with horizontal upper lugs and inclined lower lugs, an upper and lower hub for each wheel, the upper hub having horizontal lugs and the lower lug having upwardly inclined lugs, spokes fastened to the lugs on the upper hub and to the lugs on the castings, compression members secured to the lower lugs of the casting and to the similarly inclined lugs of the lower hub and the rim adapted to receive supporting hooks.

70 2. A laundry rack comprising in part a wheel formed of a circular flat metal band, an upper hub, a plurality of arms fastened on the inner periphery of the band and each arm provided with a horizontal lug and a downwardly inclined lug, an upper hub having lugs extending in the same plane as the upper lugs on said arm and a lower hub having lugs inclined similarly to the inclination of the lower lugs on the said arms, compression and tension members respectively bolted to the upper hub and the upper lugs on the arms and the compression members extending from the lugs on the lower hub to the lower lugs of the said arms and bolted thereto, and the rim adapted to have hooks bolted thereto.

75 3. A fabricated metal laundry rack com-

prising feet, a base supported by the feet and a rotatably secured central shaft in said base, two rotatable rack wheels supported by said shaft and means for locking them to the shaft, each of said wheels comprising an upper and lower hub, compression and tension members respectively bolted thereto at their one end to said hubs, a flat vertically

positioned rim, means in the form of tie arms bolted to the inner surface of the rim, said compression and tension members also bolted to said means and the rim adapted to have supporting hooks bolted thereto. ¹⁰

In testimony whereof I affix my signature.

PAUL SCHANDER.
